(57) **CLAIM**

The ornamental design for a paperboard carrier for prepared food, as shown in the drawings.

DESCRIPTION

The nature and intended use of the article in which the design is embodied is to insert a conatiner inside the cavity of the paperboard carrier. The paperboard carrier is shaped to retain the container and has handles to assist with transportation of the container.

FIG. 1 is a plan view of a paperboard carrier for prepared food prior to gluing according to the invention;

FIG. 2 is an isometric view of the paperboard carrier for prepared food after it has been folded and glued according to the invention;

FIG. 3 is an isometric view of the assembled paperboard carrier for prepared food prior to being loaded with a food container according to the invention; and,

FIG. 4 is an isometric view according to the invention, the food container shown in broken lines for illustrative purposes only and forms no part of the claimed design.
